UNITED STATES PATENT OFFICE.

EMIL R. MARKMANN AND JOHN MARKMANN, OF CHICAGO, ILLINOIS.

AUTOMATICALLY-CLOSING FURNACE-DOOR AND DEVICE FOR OPENING THE SAME.

No. 873,573.

Specification of Letters Patent.

Patented Dec. 10, 1907.

Application filed May 23, 1906. Serial No. 318,395.

To all whom it may concern:

Be it known that we, EMIL R. MARKMANN and JOHN MARKMANN, citizens of the United States, residing at Chicago, in the county of 5 Cook and State of Illinois, have invented new and useful Improvements in Automatic-ally-Closing Furnace-Doors and Devices for Opening the Same, of which the following is a specification.

10 Our invention relates to automatically closing furnace doors and devices for opening the same.

The object of the invention is to provide a novel and highly useful means adapted to 15 slidably connect furnace doors to the front plate of a furnace in a manner to permit the doors to automatically close, and to provide means by which the doors may be opened, both means being adapted to be applied to 20 any construction of furnace.

With the above and other objects in view, the invention consists in the construction, combination and arrangement of parts hereinafter fully described, claimed and illustrated in the accompanying drawings, 25 wherein:

Figure 1 is a sectional view of our invention. Fig. 2 is a sectional view on the line 2—2 of Fig. 1, the doors being opened.

30 Referring to the drawings by reference numerals, 1 designates the front plate of a furnace provided with the usual opening 2, and 3 a platform. Guides 4 are secured to the front plate 1 and are pitched downwardly 35 to cause the doors 5, which are slidably mounted therein, to automatically close.

A lever 9 is pivotally secured in a bracket 10 supported beneath the platform 3, the operating end of the lever being provided 40 with a channeled cross head 11, which has its ends provided with perforations 12. Each of a pair of links 13 has one of its ends secured to one of the doors 5 and its other end pivotally secured in the channeled head 45 11 by pins mounted in the perforations 12. In view of this connection between the lever 9 and the doors 5, a downward movement of the power end of said lever will move the doors upward in the guides 4 and clear the 50 opening 2. When the force has been removed from the power end of the lever 9,

the doors will move down the guides 4 and close the opening 2.

An engine 14 is positioned directly beneath the power end of the lever 9 and has mounted 55 therein a piston head 15. A piston rod 16 is secured to the head 15 and to the power end of the lever 9 by means of a pin and slot connection 17. A pipe 18 connects the engine 14 to a compressed air tank 19. A two-way 60 valve 20 is interposed in the pipe 18 and when in one position establishes communication between the engine 14 and the tank 19 and when in another position cuts off communication between the engine and tank. 65

When the doors are closed, the head 15 is located within the upper end of the engine 14 and when it is desired to open the doors, the valve 20 is operated to establish communication between the engine 14 and the tank 70 19, to direct compressed air into the engine above the head 15, whereupon the head 15 is moved downward. This downward movement of the head 15 elevates the operating end of the lever 9 and by virtue of the connection between the lever 9 and the doors 5, 75 opens the doors. When it is desired to permit the doors to close, the valve 20 is operated to cut off communication between the boiler and engine and a three-way valve 20^a 80 operated to establish communication between the engine and the atmosphere, whereupon the weight of the doors will automatically close the same and cause the head 15 to move upward, said valve 20^a being interposed in pipe 18 between the valve 20 and the engine. 85

To assist the automatic closing of the doors, a spring 21 is interposed between the power end of the lever 9 and the bracket 10. A bracket 22 is secured to the platform 90 3 and straddles the lever 9, the spring 21 being interposed between this bracket and the lever. By locating the spring 21 between the arms of the bracket 22 the same is prevented from lateral contortion when compressed during the operation of the lever to open the doors. To prevent the doors from closing too suddenly and bruising their opposing vertical edges, we provide a dash pot 23, the plunger of which has a pin and slot 95 connection 24 with the operating end of the lever 9. 100

A bell crank treadle lever 23^a is pivotally mounted upon the underside of the platform 3, its long arm 24^a projecting through a slot 25 in the platform and the end of its short arm 26 engaging the lever 9 at a point near its power end. The stem of the valve 20 is connected to the long arm of the lever 23^a by a rod 27, while the stem of the valve 20^a is connected to the rod 27 by a rod 28 and bell crank lever 29, said lever 29 having a pin and slot connection with the rod 27.

When it is desired to open the doors 5, the arm 24^a of the lever 23^a is forced downward, whereby, in view of the connection between said arm and the valves 20 and 20^a, the valve 20 is operated to establish communication between the engine 14 and the air tank 19, while the valve 20^a is operated to cut off communication between the engine 14 and the atmosphere. In view of the connection between the arm 24^a and the lever 9, a downward movement of said arm will impart an initial movement to the lever 9, the full movement thereof being completed by the entrance of compressed air into the engine 14. When the force applied to the arm 24^a to move it downward is removed, a spring 30 interposed between said arm and the platform 3 moves said arm upward, this upward movement closing the valve 20 and opening the valve 20^a, thus permitting the escape of the exhaust and permitting the doors 5 to close.

From the foregoing description, taken in connection with the accompanying drawings, the construction and mode of operation of the invention will be understood without a further extended description.

Changes in the form, proportions and minor details of construction may be made within the scope of the invention without departing from the spirit or sacrificing any of the advantages thereof.

Having thus described our invention, what we claim is:

1. In combination with a furnace, of automatically closing doors, a pivotally mounted lever, a connection between the operating end of said lever and the doors, an engine having connection with the power end of said lever, a pipe connecting the engine to an air tank, a valve interposed in said pipe between the engine and tank, another valve interposed between the engine and first named valve, and another lever connected to the valves and adapted to be operated to close one and open the other of said valves and to impart an initial movement to the first named lever.

2. The combination with an automatically closing furnace door, of a pivotally mounted lever, a connection between the operating end of the lever and the door, operating means connected to the power end of the

lever, and means adapted to control the operating means and by which an initial movement can be imparted to the lever.

3. The combination with an automatically closing furnace door, of a pivotally mounted lever, a connection between the operating end of the lever and the door, an operating means connected to the power end of the lever, and another lever connected to the operating means and by which said operating means can be controlled, said other lever providing means by which an initial movement can be imparted to the first named lever.

4. The combination with an automatically closing furnace door, of a pivotally mounted lever, a connection between the operating end of the lever and the door, a dash pot connected to the operating end of the lever, operating means connected to the power end of the lever, and means adapted to control the operating means and by which an initial movement can be imparted to the lever.

5. The combination with an automatically closing furnace door, of a pivotally mounted lever, a connection between the operating end of the lever and the door, operating means connected to the power end of the lever, means adapted to control the operating means and by which an initial movement can be imparted to the lever, and a spring acting upon the lever at a point adjacent its power end.

6. The combination with an automatically closing furnace door, of a pivotally mounted lever, a connection between the operating end of the lever and the door, a dash pot connected to the operating end of the lever, operating means connected to the power end of the lever, means adapted to control the operating means and by which an initial movement can be imparted to the lever, and a spring acting upon the lever at a point adjacent its power end.

7. In combination with a furnace, of downwardly inclined guides secured to the front plate of the furnace about the opening therein, doors mounted in the guides to automatically close, a pivotally mounted lever, a connection between the lever and the door, operating means connected to the power end of the lever, and means adapted to control the operating means and by which an initial movement can be imparted to the lever.

8. In combination with a furnace, of downwardly inclined guides secured to the front plate of the furnace about the opening therein, doors mounted in the guides to automatically close, a pivotally mounted lever, connection between the operating end of the lever and the doors, a dash pot connected to the operating end of the lever, operating means connected to the power end of

the lever, a treadle lever connected to the operating means, said treadle lever providing means by which the operating means can be controlled and by which an initial movement 5 can be imparted to the first named lever, and a spring acting upon the first named lever at a point adjacent its power end.

In testimony whereof, we affix our signature in presence of two witnesses.
